UNITED STATES PATENT OFFICE

CLARENCE D. DAVIS, OF LOS ANGELES, CALIFORNIA

INTERNAL COMBUSTION ENGINE

Application filed August 17, 1929. Serial No. 386,717.

My invention relates to improvements in internal combustion engines, and particularly in that type of engine in which secondary pistons opposed to the main power pistons are used, its essential object being to provide improvements in the construction of and operating means for the secondary pistons.

In the accompanying drawings, forming part of this specification:

10 Figure 1 is a central longitudinal sectional view of a four-cylinder unit embodying my features of construction.

Figure 2 is a vertical cross section taken on line 2—2 of Figure 1.

15 Figure 3 is an end view of the engine with the cover partly broken away.

Figure 4 is a horizontal sectional view on line 4—4 of Figure 1, and

20 Figures 5 to 8 are diagrammatic views illustrating successive positions of the engine parts.

Referring to the drawings, A represents the casing of the engine, and 10 a four-throw crankshaft with the throws arranged 90 degrees apart.

The engine embodies cylinders 12, 13, 14 and 15, containing power pistons 16, 17, 18 and 19, operatively connected to the crankshaft by rods 20, 21, 22 and 23; secondary 25 pistons 24, 25, 26 and 27 are positioned in the cylinders and form the heads thereof, said pistons carrying plungers 28, 29, 30 and 31 respectively, which operate in cylinders 32, 33, 34 and 35 respectively. A conduit 36 connects the heads of the cylinders 32, 33, 34 and 35. A conduit 37 connects the lower ends of the cylinders 32 and 33 with the cylinder 38, and a conduit 39 connects the lower ends of the cylinders 34 and 35 with the cylinder 40. Operating within the cylinders 38 and 40 are pistons 41 and 42, operatively connected with the crankshaft 43 by rods 44 and 45.

The crankshaft 43 has two crank-throws arranged at 180 degrees and is driven from the crankshaft 10 at twice the speed of said crankshaft by the connecting gears 46 and 47.

The conduit 36 contains a fluid for transmission of movement between the plungers 28 to 31 inclusive. The conduit 37 contains

a fluid for the transmission of movement from the piston 41 to the plungers 28 and 29. The conduit 39 contains a fluid for the transmission of movement from the piston 42 to the plungers 30 and 31.

Leakage of liquid from the conduits 36, 37 and 39 is compensated for through the check valves 48, 49 and 50 from a source not shown. Any suitable means may be provided for accomplishing the result just described.

A rotary valve 51 is driven at the speed of the crankshaft 10 by gears 47 and 53 and gears 54 and 55. The shaft 56 carrying the gears 53 and 54 is mounted in the cover 57. Rotary valve 51 controls ports 52 that are formed in the wall of the engine cylinder and which ports function as combined exhaust and gaseous fuel inlet ports.

The sequence of operations in each power cylinder is as follows:

The power piston, at approximately half-way on its down-stroke opens the ports 52 in its cylinder allowing relief of gas pressure through the rotary valve. When the pressure has blown down, the opposing piston in the cylinder will start its down stroke, or exhaust stroke, and the power piston and the opposing piston will complete their down strokes at approximately the same time. The secondary piston will then travel upward at approximately twice the speed of the power piston so that a charge of gas will be drawn in between said pistons through the rotary valve 51 and the ports 52 in the power cylinder. At approximately the time the secondary piston completes its up-stroke the power piston will close the ports 52 in the power cylinder and start compression of charge. On completion of compression the charge is fired and the cycle repeated.

Referring to Figure 5, the piston 16 in the cylinder 12 is in position to start on the power stroke; the piston 17 in the cylinder 13 has completed its down-stroke and the piston 25 has forced out the burnt charge; the piston 18 is on the down or power stroke, and the piston 19 is on the compression stroke.

During the next quarter revolution of the crankshaft 10, the piston 42 will complete its up-stroke forcing fluid through the conduit

39 thereby causing up-stroke of the plunger 29 carrying the piston 25. The separation of the pistons 17 and 25 causes intake of gas charge through the rotary valve and ports in the cylinder 13. The up-stroke of the plunger 29 will create a fluid pressure in the conduit 36. As an equal pressure is acting on the under sides of the plungers 28 and 29, the relief for pressure in the conduit 36 will be through the down-stroke of the plunger 30 or 31. Since compression will take place in the cylinder 15, and since the ports in the cylinder 14 will be opening to permit exhaust of gases, the plunger 30 will be forced down carrying the piston 26 on its exhaust stroke. The pistons of the engine will then be in the positions shown in Figure 6.

During the next quarter revolution of the crankshaft 10, the piston 41 will complete its up-stroke forcing the fluid through the conduit 37 causing up-stroke of the plunger 30 carrying the piston 26. The separation of the pistons 18 and 26 causes intake of gas charge through the rotary valve and ports in the cylinder 14. The up-stroke of the plunger 30 will create a fluid pressure in the conduit 36. As an equal pressure is acting on lower ends of the plungers 30 and 31, the relief for pressure in the conduit 36 will be through the down stroke of the plunger 28 or 29. Since compression will take place in the cylinder 13, and since the ports in the cylinder 12 will permit exhaust of gases, the plunger 28 will be forced down carrying the piston 24 on its exhaust stroke. The pistons of the engine will then be in the positions shown in Figure 7.

During the next quarter revolution of the crankshaft 10, the piston 42 will complete its upstroke forcing the fluid through the conduit 39, causing upstroke of the plunger 28, carrying the piston 24. The separation of the pistons 16 and 24 causes intake of gas through the rotary valve and ports in the cylinder 12. The up-stroke of the plunger 28 will create a fluid pressure in the conduit 36. As an equal pressure is acting on the lower ends of the plungers 28 and 29, the relief for pressure in the conduit 36 will be through the down-stroke of the plunger 30 or 31. Since compression will take place in the cylinder 14, and since the ports in the cylinder 15 will permit exhaust of gases, the plunger 31 will be forced down carrying the piston 27 on its exhaust stroke. The pistons of the engine will then be in the positions shown in Figure 8.

During the next quarter revolution of the crankshaft 10, the piston 41 will complete its up-stroke forcing fluid through the conduit 37 causing up-stroke of the plunger 31 carrying the piston 27. The separation of the pistons 19 and 27 causes intake of gas through valve and ports in the cylinder 15. The up-stroke of the plunger 31 will create a fluid pressure in the conduit 36. As an equal pres-

sure is acting on the lower ends of the plungers 30 and 31 the relief for pressure in the conduit 36 will be through the down stroke of the plunger 28 or 29. Since compression will take place in the cylinder 12 and since the ports in the cylinder 13 will permit exhaust of gas, the plunger 29 will be forced down carrying the piston 25 on its exhaust stroke. The pistons of the engine will then be in the positions shown in Figure 5.

The down travel of the pistons 24, 25, 26 and 27 is checked by pistons 41 and 42 through the medium of the fluid in conduits 37 and 39 or by other forces. The up travel of the pistons 24 to 27 inclusive, is checked by pistons 41 and 42 and by fluid trapped between the plungers carrying said pistons and the contracted areas of the cylinders in which said plungers operate.

Referring to Fig. 1, in a two cylinder unit comprising cylinders 12 and 13 with their pistons, and essential parts, the conduit 36 would lead to cylinder 40. In three or six cylinder units the pistons corresponding to 41 and 42 in Fig. 1 would operate at three times the frequency of the power pistons, and ports in power cylinders would be opened when power pistons had completed approximately two-thirds of their down or power strokes.

It will be understood that the principle of this invention may be applied to that type of engine wherein a charge of air is taken into the cylinder and fuel forced into said charge, at approximately the time of completion of compression of said charge.

Although I have described the preferred form of my invention herein, it is to be understood that I do not limit myself to the particular construction shown, but may modify the same within the general scope of the invention as set forth in the following claims.

I claim as my invention:

1. In an internal combustion engine, the combination of a crankshaft, a cylinder with a piston therein operatively connected to the crankshaft for performing power and compression strokes, a piston in said cylinder opposed to said power piston, liquid pressure means for operating said last mentioned piston to draw in and expel gas from the cylinder, and valvular means for controlling the exhaust and intake of gas.

2. In an internal combustion engine, the combination of a crankshaft, a plurality of cylinders with pistons therein operatively connected to the crankshaft for performing power and compression strokes, pistons in said cylinders opposed to said power pistons, means for applying liquid pressure to operate said last mentioned pistons for drawing into and expelling gas from the cylinder, means for equalizing said pressure on certain of the last mentioned pistons, and valvular means for controlling the exhaust and intake of gas.

3. In an internal combustion engine, the

- combination of a powershaft, a plurality of cylinders with pistons therein operatively connected to the powershaft for performing power and compression strokes, pistons in said cylinders opposed to said power pistons, reciprocating means operated by the engine for applying liquid pressure to alternately operate said last mentioned pistons for drawing into and expelling gas from the cylinders, and valvular means in connection with the cylinders for controlling the exhaust and intake of gas.
4. In an internal combustion engine, the combination of a crankshaft, and a cylinder with opposed pistons therein; one of said pistons being operatively connected to the crankshaft for performing power and compression strokes, and the other piston being operatively connected to the crankshaft through an intermediate liquid, for drawing into and expelling gas from said cylinder.
5. In an internal combustion engine, the combination of a crankshaft; a cylinder with opposed pistons therein, one of said pistons being operatively connected to the crankshaft for performing power and compression strokes; a liquid above the other said piston; and piston means operatively connected to the crankshaft for causing said liquid to actuate said second piston for drawing into and expelling gas from said cylinder.
6. In an internal combustion engine, the combination of a crankshaft, a cylinder with a power piston therein operatively connected to the crankshaft, a second piston opposed to said power piston adapted to reciprocate in said cylinder, liquid pressure means for operating the second piston, and valvular inlet and exhaust means for said cylinder; said power piston performing its power stroke while said second piston is at rest and said second piston being arranged to expel gas from the cylinder on its downstroke and to draw in gas on its up-stroke while the power piston is at the lower end of its travel.
7. In an internal combustion engine, the combination of four cylinders with power pistons therein; pistons therein opposed to said power pistons, and operable through plungers adapted for reciprocation in tubes having their heads connected by a common manifold and their opposite ends connected in pairs by manifolds in communication respectively with two hydraulic cylinders; pistons within said hydraulic cylinders adapted to operate at twice the frequency of the power pistons; and a liquid within said tubes, manifolds, communications, and hydraulic cylinders for operating said plungers by displacement of said hydraulic pistons.
8. In an internal combustion engine, the combination of a plurality of power cylinders, power pistons in said cylinders, secondary pistons opposed to said power pistons, a liquid in connection with said secondary pistons, and means for imparting alternating impulses to said secondary pistons through the medium of said liquid.
9. In an internal combustion engine, the combination of an even number of cylinders containing power pistons and opposed secondary pistons, plungers carried by said secondary pistons, tubes containing said plungers, a manifold connecting the heads of said tubes, manifolds connecting equal numbers of the opposite ends of said tubes, means for actuating said plungers through the medium of a liquid in said tubes and manifolds, and valvular means in connection with said cylinders for controlling the intake and exhaust of gas.
10. In an internal combustion engine, the combination with a plurality of cylinders and power pistons operating therein, of auxiliary pistons operating in said cylinders opposite the power pistons to perform intake and exhaust strokes and means for operating said auxiliary pistons to cause them to perform intake and exhaust strokes, which means comprises plunger mechanism reciprocated by the engine in timed relation thereto and a fluid pressure medium actuated by said reciprocating plunger mechanism for transmitting the actuating force to said auxiliary pistons.
11. In an internal combustion engine, the combination with a plurality of cylinders and power pistons operating therein, of auxiliary pistons operating in said cylinders opposite the power pistons to perform intake and exhaust strokes and means for operating said auxiliary pistons to cause them to perform intake and exhaust strokes, which means comprises plunger mechanism continuously reciprocated by the engine in timed relation thereto and a fluid pressure medium actuated by said reciprocating plunger mechanism for transmitting an actuating force to said auxiliary pistons.
- In testimony whereof I affix my signature.
- CLARENCE D. DAVIS.
